UNITED STATES PATENT OFFICE

2,403,260

VALVE GUIDE OF INTERNAL-COMBUSTION ENGINES

Hubert Noel Charles, Edgbaston, Birmingham, England, assignor to The Austin Motor Company Limited, Northfield, Birmingham, England

Application October 11, 1944, Serial No. 558,191
In Great Britain September 6, 1943

9 Claims. (CL 123—188)

1

The invention relates to valve guides of internal combustion engines, and has for its object to effect improvements therein chiefly with a view to reducing valve noise.

It is well known that, if the valve guide clearance is made very small, the valve stem is liable to stick due to its lateral expansion when heated, because the valve guide, being set in the cylinder head or cylinder block, cannot expand freely in a lateral direction, and furthermore its temperature will be governed by that of the cylinder head or cylinder block which will, under running conditions, be less than that of the valve stem, especially if, as is often the case, the guide is in contact with cooling liquid. As a consequence it has heretofore been found necessary to allow considerable freedom of the stem within the guide, with the result that a good deal of unwanted noise is produced and leakage of oil and gases between the valve stem and the guide may take place.

In order to avoid the above disadvantages, and according to this invention, the valve guide is made in two parts, one of which is an inner part set in the cylinder head or cylinder block (as the case may be) in the usual manner, except that it may be arranged to project a short distance from the outer surface of the part of the engine in which it is set. Free or normal clearance C' is allowed between such inner part of the guide and the valve stem passing through it. The other part of the valve guide is an outer part so positioned that it is free to expand laterally, for the reason that it is not fitted within the cylinder head or cylinder block. It is preferably placed outside such cylinder head or cylinder block being spigoted on to the aforesaid projecting portion of the inner part of the guide.

The outer part of the guide may be held in place in any manner which permits of its free lateral expansion, but preferably it has a flange formed at its inner end on which the valve spring bears, the flange acting as the inner locating washer for the spring, and also as the means for keeping the outer part of the guide in place. The clearance between such outer part of the guide and the valve stem may be much smaller than the usual clearance heretofore provided between valve guides and the valve stems guided therein.

The said outer part of the guide may be of bronze or other metal having a higher co-efficient of expansion than the valve stem, and the outer part will tend to become of the temperature of the valve stem and will expand accordingly and maintain, or even slightly increase, the clearance, as the valve stem heats up.

2

The smallness of the clearance between the valve stem and the outer part of the guide secures the double advantage of reduced noise without tendency of the valve stem to stick and less liability for oil and gases to leak along the guide.

A convenient embodiment of the invention is described with reference to the drawing herewith which is a vertical section through a cylinder head of an internal combustion engine and through one of the valves thereof.

In this drawing:

A indicates a cylinder head of conventional form having inserted therein a valve seat a. B indicates the usual water cooling space. C is one of the valves also of conventional form being impelled towards the valve seat a by coil springs D. c is the valve stem.

E is the lower or inner portion of the valve guide and it is set as a tight fit in a hole bored to receive it in the cylinder head. The portion E of the guide has a short portion e extending above the top of the head.

The stem c is arranged to have free or normal clearance C' in the guide portion E, the clearance being sufficient to ensure that lateral expansion of the stem under working conditions will not cause sticking of the stem in the guide.

The guide portion E may be formed of cast iron, steel or other metal.

F is the upper portion of the valve guide being formed of bronze or other metal having a relatively high co-efficient of expansion. It is bored to receive the valve stem as a relatively close but free sliding fit. It is recessed at f to receive the upper end e of the guide portion E as a good fit; and the recess f is carried up a short distance beyond the portion e so as to leave an annular recess or "heat break" G between the top of the portion E and the top of the recess f.

A stepped flange f' is formed on the lower end of the guide portion F, the springs D bearing down thereon and being located thereby. At the upper end of the stem c there is fitted the usual stepped washer H and split cotters h.

The lower part of the valve stem c will receive heat from the valve and consequently its temperature will be relatively high, but owing to its free clearance C' in the guide portion E, it can expand freely without danger of sticking in the guide. The guide portion F will receive heat from the upper part of the stem; but owing to its relatively high co-efficient of expansion it will always leave a working clearance and, owing to the "heat break" G, it will receive comparatively little heat from the guide portion E. As a result

the clearance between the stem c and the guide portion F can be relatively small so ensuring a good seal against the passage of oil and gases. The small clearance also ensures a very accurate control over the movements of the valve, so that it will come accurately on to its seat which greatly reduces noise.

Having fully described my invention what I claim and desire to secure by Letters Patent is:

1. A valve guide of an internal combustion engine said valve guide comprising two separate parts, one of said parts being an inner part set in a fixed part of the engine and having the usual clearance between its inner surface and the stem of the valve with which it is associated, and the other of said parts being an outer part mounted in a manner to allow of its free lateral expansion and having a clearance less than that of the said inner part, an axial recess in the inner end of said outer part and an extension of said inner part entered into said recess.

2. A valve guide of an internal combustion engine said valve guide comprising two separate parts, one of said parts being an inner part set in a fixed part of the engine and having the usual clearance between its inner surface and the stem of the valve with which it is associated, and the other of said parts being an outer part mounted in a manner to allow of its free lateral expansion and having a clearance less than that of the said inner part, an axial recess in the inner end of said outer part and an extension of said inner part entered into said recess, said extension being shorter than said recess so as to leave a space between the end of the recess and the end of the said extension.

3. A valve guide of an internal combustion engine said valve guide comprising two separate parts, one of said parts being an inner part set in a fixed part of the engine and having the usual clearance between its inner surface and the stem of the valve with which it is associated, and the other of said parts being an outer part mounted in a manner to allow of its free lateral expansion and having a clearance less than that of the said inner part, said inner and outer parts being spaced sufficiently to form a heat break, and an external annular flange at the inner end of the said outer part acting as an abutment for the usual valve spring or springs.

4. A valve guide of an internal combustion engine said guide being transversely divided into two separate parts both directly surrounding the valve stem and slightly spaced from each other to form a heat break, the one part being an inner part, that is to say nearer to the valve head than is the other part and set in a fixed part of the engine, and having the usual clearance between it and the surface of the valve stem, the other of said parts being an outer part mounted in a manner to allow of its free lateral expansion and having a clearance less than that of the said inner part.

5. A valve guide of an internal combustion engine said guide being transversely divided into two separate parts both directly surrounding the valve stem and slightly spaced from each other to form a heat break, the one part being an

inner part, that is to say nearer to the valve head than is the other part and set in a fixed part of the engine, and having the usual clearance between it and the surface of the valve stem, the other of said parts being an outer part mounted in a manner to allow of its free lateral expansion and having a clearance less than that of the said inner part, and said outer part mounted outside the part of the engine in which the inner part is set.

6. A valve guide of an internal combustion engine said guide being transversely divided into two separate parts both directly surrounding the valve stem and slightly spaced from each other to form a heat break, the one part being an inner part, that is to say nearer to the valve head than is the other part and set in a fixed part of the engine, and having the usual clearance between it and the surface of the valve stem, the other of said parts being an outer part mounted in a manner to allow of its free lateral expansion and having a clearance less than that of the said inner part, and said outer part having a coefficient of expansion greater than that of the valve stem.

7. A valve guide of an internal combustion engine said valve guide comprising two separate parts one of said parts being an inner part set in a fixed part of the engine, and having the usual clearance between its inner surface and the stem of the valve with which it is associated, and the other of said parts being an outer part mounted in a manner to allow of its free lateral expansion and having a clearance less than that of the said inner part, an axial recess in the inner end of said outer part and an extension of said inner part entered into said recess.

8. A valve guide of an internal combustion engine said valve guide comprising two separate parts one of said parts being an inner part set in a fixed part of the engine, and having the usual clearance between its inner surface and the stem of the valve with which it is associated, and the other of said parts being an outer part mounted in a manner to allow of its free lateral expansion and having a clearance less than that of the said inner part, an axial recess in the inner end of the said outer part and an extension of said inner part entered into said recess, said extension being shorter than said recess so as to leave a space between the end of the recess and the end of the said extension.

9. A valve guide of an internal combustion engine said guide being transversely divided into two separate parts both directly surrounding the valve stem and slightly spaced from each other to form a heat break, the one part being an inner part, that is to say nearer to the valve head than is the other part and set in a fixed part of the engine, and having the usual clearance between it and the surface of the valve stem, the other of said parts being an outer part mounted in a manner to allow of its free lateral expansion and having a clearance less than that of the said inner part, and an external annular flange at the inner end of the said outer part acting as an abutment for the usual valve spring or springs.

HUBERT NOEL CHARLES.
